UNITED STATES PATENT OFFICE

149,901

DESIGN FOR A MARLINESPIKE

Otto Olsen, Detroit, Mich.

Application December 30, 1946, Serial No. 135,848

Term of patent 14 years

(Cl. D54—2)

To all whom it may concern:

Be it known that I, Otto Olsen, a citizen of the United States, residing in Detroit, in the county of Wayne and State of Michigan, have invented a new, original, and ornamental Design for a Marlinespike, of which the following is a specification, reference being had to the accompanying drawing, forming a part thereof, wherein:

Fig. 1 is an end view, looking at the handle end, of a marlinespike, showing my new design;

Fig. 2 is a side elevational view;

Fig. 3 is a side elevational view taken in a plane 90° about the axis from the view shown in Fig. 2; and

Fig. 4 is a transverse sectional view of the marlinespike shown in the preceding figures, taken on the line 4—4 of Fig. 2.

I claim:

The ornamental design for a marlinespike, as shown.

OTTO OLSEN.
